UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,115,211.

Specification of Letters Patent. Patented Oct. 27, 1914.

Application filed May 25, 1914. Serial No. 840,793.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

- 10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal 15 to form a slug or linotype against the matrices which produce the type characters thereon, and the matrices thereafter returned through distributing mechanism to the magazine from which they started.
- 20 More particularly, it relates to such machines when equipped with a plurality of movable magazines, any one of which may be shifted into operative relation to the assembling devices. As shown for instance in 25 U. S. Letters Patent to J. R. Rogers, No. 792,851, the several magazines are moved relatively to a single throat, through which the matrices pass from the selected one to the further assembling devices, and the 30 throat is provided with a single series of escapement devices adapted to control the release of the matrices from all the magazines as they are successively brought into position. In machines of the kind illustrated, in the Rogers patent, and to prevent 35 the mixing of fonts, means are provided whereby matrices remaining in the throat are restored to their proper magazine, before it is shifted and another one takes its 40 place. In order to obviate this necessity, I employ an arrangement of escapement devices, the operation of which insures the delivery of the matrix in the throat, leaves the throat empty, and also effects the retention of the lowermost matrix in the magazine, so as to leave the latter ready for free and unimpeded shifting. The particular 45 means for effecting this result will be described in the specification and finally pointed out in the claims.

In the accompanying drawing, I have shown my invention in preferred form and by way of example, and as applied to the form of machine already referred to, but many changes and variations may be made 50 therein, and in its mode of application, which will still be comprised within its spirit. Thus, the particular arrangement and construction of the parts may be varied, or its may be applied to other forms of 55 typographical machines, such as typesetters, typecasters and the like, which handle type or dies, instead of matrices. Generally speaking, I desire it to be understood that I do not limit myself to any 60 particular form or embodiment, except in so far as such limitations are specified in the claims.

Referring to the drawing: Figure 1 is a vertical section through the lower part of 75 the magazines, etc., of a linotype machine, having my invention embodied therein; and Fig. 2 is a similar view showing the parts in different position.

As is usual in machines of this style, the 80 matrices X are stored in a plurality of movable magazines A, the shifting of which brings the selected one into operative relation to the assembling devices. During this movement the matrices are held in place by 85 the rock shafts or locking devices B, which may then be manipulated to free the matrices of the selected magazine. The release of the matrices is controlled by escapement devices connected to the stationary 90 throat F through which the matrices pass into the raceway K.

The parts so far described, and their mode of operation, except in so far as subsequently pointed out, are or may be of any 95 preferred or necessary form, and in themselves constitute no part of my invention.

The individual escapements each comprise a pivoted lever C, an upper pawl D, and a lower pawl E, which pawls are alternately projected into the throat F, in the manner well understood in the art. The illustrated means for effecting the rocking movement of the lever C comprise the spring G normally tending to move the upper pawl 100 D into operative position, and the reed J and lever H, the action of which withdraws the pawl D and projects the lower pawl E into the throat. It will be noted that the pawls D and E are so located that the upper one 105

110

stands normally beneath the lowermost matrix in the magazine and in engagement with the edge of the matrix previously released therefrom, which condition of the parts is shown in Fig. 1. It will also be observed that the opposite edge of the channel in the throat F is cut away or inclined at F', so that as the pawl D moves inwardly against the matrix, the latter is displaced edgewise. As the pawl E is simultaneously retracted, the matrix passes from the throat and the latter is cleared. The intermediate or abnormal position of the escapement is shown in Fig. 2, wherein the upper pawl D is withdrawn and the lowermost pawl E projected, which permits the descent of the lowermost matrix in the magazine and its arrest by the pawl E. The return movement restores the parts to the position shown in Fig. 1, allowing the released matrix to drop from the throat and insuring the retention of the next matrix in the magazine. It will be seen that due to this arrangement of the parts, the magazine is always free and ready to be shifted, and that the necessity no longer exists for restoring matrices to it from the throat F. If it be desired to move it to an operative position, all that is required is the locking of the matrices therein by the manipulation of the rock shaft B.

As previously stated, I have shown my invention only in preferred form and by way of example, and as adapted to a specific kind of machine. However, many modifications and alterations therein, and in its mode of adaptation, will suggest themselves to those skilled in the art, without departure from its scope.

Having thus described my invention, its construction and mode of operation, what I claim and desire to secure by Letters Patent of the United States, is as follows:

1. In a typographical machine, the combination of a column of type or matrices, and an escapement to control their release, the said escapement comprising two pawls which are projected alternately into the path of movement of the type or matrices, and one of which pawls shifts the matrices edgewise in effecting their release.

2. In a typographical machine, the combination of a column of type or matrices, and an escapement to control their release, the said escapement comprising two pawls which are projected alternately into the path of movement of the type or matrices, the upper one of said pawls standing normally in engagement with the lowermost matrix in the column and acting to shift it edgewise in its subsequent return to normal position.

3. In a typographical machine, the combination of a magazine to contain the type or

matrices, and an escapement mounted externally of the magazine to control their release therefrom, the said escapement comprising two pawls which are projected alternately into the path of movement of the type or matrices, the upper one of said pawls standing normally in engagement with the lowermost matrix in the magazine and acting to shift it edgewise in its subsequent return to normal position.

4. In a typographical machine, the combination of a magazine for the type or matrices, an exterior throat to receive them therefrom, and an escapement comprising two pawls acting in the throat to control the passage of the type or matrices therethrough, the upper one of said pawls standing normally in engagement with the lowermost matrix in the magazine and acting to shift it edgewise in its subsequent return to normal position.

5. In a typographical machine, the combination of a magazine for the type or matrices, an exterior throat to receive them therefrom, and an escapement comprising two pawls acting in the throat to control the passage of the type or matrices therethrough, one of said pawls adapted to shift them edgewise in their passage, and the said throat being cut away at its farther side to permit such edgewise shifting of the type or matrices.

6. In a typographical machine, the combination of a stationary throat, a plurality of magazines movably arranged to bring one or another thereof into operative relation to the throat, and an escapement comprising two pawls acting in the throat to control the passage of the type or matrices therethrough, the upper one of said pawls standing normally in engagement with the lowermost matrix in the selected magazine, and the throat being formed to permit said matrix to be shifted edgewise by the upper pawl in its subsequent return to normal position.

7. In a typographical machine, the combination of a magazine for the type or matrices, and a reciprocating escapement mounted exteriorly of the magazine and comprising two pawls, the upper one of which stands, normally in engagement with the lowermost matrix in the magazine, the matrices being shiftable edgewise by the upper pawl in its subsequent return to normal position.

In testimony whereof, I have affixed my signature in presence of two witnesses.

DAVID S. KENNEDY.
